US00D731703S

(12) **United States Design Patent**
Yang

(10) **Patent No.:** **US D731,703 S**
(45) **Date of Patent:** **** Jun. 9, 2015**

(54) **ATTACHMENT LENS FOR LED**

(71) Applicant: **Guangzhou North and South Lighting Technology Co., Ltd.**, Guangzhou, Guangdong (CN)

(72) Inventor: **Yanyan Yang**, Guangzhou (CN)

(73) Assignee: **Guangzhou North and South Lighting Technology Co., Ltd.**, Guangzhou (CN)

(**) Term: **14 Years**

(21) Appl. No.: **29/498,358**

(22) Filed: **Aug. 1, 2014**

(51) LOC (10) Cl. **26-99**

(52) U.S. Cl.

USPC **D26/120**

(58) **Field of Classification Search**

USPC D26/9, 10, 12, 13, 15, 16, 24, 51, 61, D26/72, 76, 80, 81, 85, 86, 88, 90, 113, 118, D26/119, 120, 122, 128, 129, 138, 143,

(57) **CLAIM**

The ornamental design for an attachment lens for LED, as shown and described.

DESCRIPTION

FIG. 1 is a front and right side perspective view of an attachment lens for LED showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof; and,

FIG. 7 is a right side elevation view thereof.

1 Claim, 5 Drawing Sheets
